UNITED STATES PATENT OFFICE.

RAYMOND W. DULL, OF AURORA, ILLINOIS, ASSIGNOR TO STEPHENS-ADAMSON MFG. CO., OF AURORA, ILLINOIS, A CORPORATION OF ILLINOIS.

FUEL-LIGHTER.

1,164,934.

Specification of Letters Patent. Patented Dec. 21, 1915.

Application filed June 16, 1910. Serial No. 567,284.

To all whom it may concern:

Be it known that I, RAYMOND W. DULL, a citizen of the United States of America, and resident of Aurora, Kane county, Illinois, 5 have invented a certain new and useful Improvement in Fuel-Lighters, of which the following is a specification.

My invention relates to apparatus for unloading boats.

10 It relates more particularly to fuel lighters for transferring coal to a steamboat. This has been done in various ways.

The object of my invention is to provide a boat or lighter in which the coal or other 15 commodity is held in bins, and in which means are provided for discharging the contents of any particular bin, comprising a spout that will deliver the same at either side of the boat, whereby the coal or other 20 commodity may be delivered to a steamship or other structure, as will hereinafter more fully appear.

To the foregoing and other useful ends, 25 my invention consists in matters hereinafter set forth and claimed.

In the accompanying drawings—Figure 1 is a side elevation of a fuel lighter embodying the principles of my invention. Fig. 2 is a plan of the said fuel lighter. Fig. 3 is 30 an enlarged longitudinal section of the tower portion of the boat, showing a portion of the elevator housing broken away to show the elevator. Fig. 4 is a vertical cross-section on line 4—4 in Fig. 3. Fig. 5 is a 35 plan of the housing of the elevator shown in Figs. 3 and 4, showing the relation of the two spouts.

As thus illustrated, my invention comprises a boat A of any suitable form of construction. The interior of said boat is divided transversely to provide a series of bins B, which are adapted to hold coal or any other commodity, and which have their lower ends provided with gates indicated at 40 b, whereby each bin can be opened to discharge its contents independently of the other. In this way, means are provided for controlling the discharge from the compartments to the conveyers. The tower C is 45 situated amidships, and contains a bucket elevator D. The conveyers E extend longitudinally of the boat, at the bottom thereof, below the bins. These conveyers are adapted to deliver the coal or other commodity 50 to the lower end of the elevator D, their ends

being arranged to overhang the lower transverse portions of the elevator, and are operated in any suitable manner. The boom F contains a conveyer f provided with pans or buckets which receive the coal or other commodity from a spout f¹, which latter is inclosed within the tower and receives the coal from the elevator. This boom is adapted to be swung from one side of the boat to the other, and is provided with a spout f² 60 for delivering the coal or other commodity to a steamship or other structure. A cable connection f³ of any suitable character is provided for raising and lowering the said boom. The conveyers E and f can be of any 65 suitable known or approved construction. They are, however, preferably of the kind which are provided with pans or buckets, as shown in Fig. 3. The elevator is provided with an overflow spout G, whereby if the coal backs up in the spout f¹ it will overflow the wall between the two spouts and pass from the spout f¹ and fall into the spout G and then into the bin g, the two spouts being out of alinement, as shown in Fig. 4, 70 and in Fig. 5, thus preventing breakage of the machinery. For this purpose both spouts are open at the tops of their inner end portions, in other words, the tops or upper ends of the spouts are arranged side 75 by side, whereby the materials may overflow from the one spout to the other. Ordinarily, the coal is discharged in the direction of arrow No. 1 in Fig. 5, but if the coal backs up in the spout f¹, it then overflows in the 80 spout G, as indicated by arrow No. 2, and as previously described.

The tower C contains the devices, of any 85 suitable character, for controlling the operation of the conveyers E and f, and the elevator D, so that the discharge of the coal from the lighter may be efficiently and easily controlled. As shown, the lighter has an after-cabin H for the engine-room, and a forward-cabin or pilot-house I, as shown 90 in Fig. 1. The usual equipment is provided for propelling and steering the boat. It can be loaded in any suitable manner. Then by opening the gate of any particular bin, the 95 contents thereof can be discharged from a spout f² into the hold of a steamship or delivered to some other structure. Thus the 100 quantity of coal or other material can be accurately measured, and one bin or two bins or more can be discharged at a moment's 105 110

notice. In this way, lightering is greatly facilitated. The boat can, of course, be used for handling other kinds of material.

As shown in Fig. 4, the bucket elevator D 5 hangs from the sprockets d, and its lower end is left to run in a loose loop. The ends of the conveyers E extend into said loop. A housing d¹ incloses and keeps the elevator in place—that is, prevents it from swinging laterally of the boat. This housing is 10 inclosed by the tower C. Any suitable transmission can be used for driving the said elevator at the desired speed. The spout G, as explained, prevents the undesirable accumulation of material in the elevator spout f¹ when the boom is not carrying off the material fast enough.

I do not limit or confine myself to the exact construction shown and described.

20 What I claim as my invention is:

1. A boat divided into compartments forming bins, conveyers for receiving the contents of the bins, means for controlling the discharge of the contents from the bins, 25 an elevator for receiving the contents from the conveyers, the ends of the conveyers overhanging the transversely arranged lower portion of the elevator, a boom provided with a conveyer for receiving the contents 30 from the elevator, and a spout for the end of said boom, whereby the contents of any bin can be discharged at either side of the boat.

2. A boat provided with a series of compartments, a tower containing an elevator, 35 a conveyer for receiving the contents of said compartments, adapted to deliver the same to the said elevator, the delivery end of the conveyer overhanging the transverse lower portion of the elevator, a swinging boom 40 carried by the tower, a conveyer in the boom, adapted to receive the contents from the elevator, and a spout at the end of the boom.

3. A boat having the interior thereof divided into compartments, a conveyer 45 traveling under said compartments, means for controlling the discharge from the compartments to the conveyer, said conveyer

provided with pans or buckets, and means traveling transversely of the boat and running under the discharge end of the conveyor, for taking the cargo from the pans or buckets.

4. A boat provided centrally with a tower, an elevator in said tower, a series of bins fore and aft of said tower, conveyers below 55 said bins, adapted to deliver the contents thereof to said elevator, the ends of the conveyers being arranged to overhang the lower transverse portion of the elevator, a boom swung from the rear of said tower, a 60 conveyor in said boom, adapted to receive the contents of the bins from the said elevator, and a spout for the outer end of the boom.

5. A boat provided with an elevator tower, 65 an endless bucket elevator in said tower, which elevator is hung at the top and arranged to run in a loose loop at the lower end thereof, a swinging discharge boom, means for delivering from the top of the elevator to said boom, a conveyor extending 70 along the bottom of the boat and into the said loop, and a series of holding bins disposed in a row above said conveyor.

6. A boat provided with an elevator tower, 75 an endless bucket elevator in said tower, which elevator is hung at the top and arranged to run in a loose loop at the lower end thereof, a swinging discharge boom, means for delivering from the top of the elevator to said boom, a conveyor extending 80 along the bottom of the boat and into the said loop, a series of holding bins disposed in a row above said conveyor, a housing for said elevator, and a tower for inclosing said housing, said boom being mounted immediately in rear of said tower and adapted to swing from one side of the boat to the other.

Signed by me at Chicago, Illinois, this 11th day of June, 1910.

RAYMOND W. DULL.
